LETTERING, DRAWING, WRITING, AND
MARKING PEN

Louis M. Snell, Parma Heights, Ohio

Application December 29, 1932, Serial No. 649,412

1 Claim. (Cl. 120—113)

This invention relates to certain new and useful improvements in lettering, drawing, writing and marking pens, particularly adapted for use in connection with sign writing of a commercial nature.

The primary object of this invention is to provide a device of the above mentioned character adapted to allow the use of opaque colors in lettering a feat which has heretofore been impossible with present day lettering pens.

A further object of this invention is to provide a pen point having an adjustable feeding device formed of a transparent flexible material preferably celluloid or nitro-cellulose material.

15 A still further object of this invention is to provide a pen point formed of celluloid or the like stamped from a sheet of material and bent so as to be received in a tubular holding member.

A further object of this invention is to provide 20 a pen point of the above mentioned character having a feeding device formed of the same material and secured to a metal band adjustably secured to the tubular holding member whereby the feeding device may be adjusted longitudinally 25 relative to the point or writing portion of the pen point.

A still further object of this invention is to provide a writing, lettering and marking pen point with a writing surface having parallel slits extending inwardly therefrom which assist the feeding action.

A still further object of this invention is to provide a marking and lettering pen point which is extremely flexible and which permits the use of 35 heavy opaque color or liquid as well as the lighter inks and fluids.

A still further object of this invention is to provide a marking and lettering pen of the character described having a feeding device adapted 40 to be adjusted so close to the writing surface of a pen point that the fluid will flow more freely and heavy so that when the writing fluid is dry the marking thereby made has the appearance of embossed lettering, which is actually raised on the 45 surface of the paper or board upon which the pen is being used.

A still further object of this invention is to provide a combined feeding and agitating nib to perform the function of feeding the ink or writing fluid as well as agitating the same and preventing the hardening and congealing thereof.

Other objects and advantages of the invention will become apparent during the course of the following description, forming a part of this 55 specification and in which,

Figure 1 is a top elevational view of the marking, lettering and writing pen illustrating the position of the feeding device relative thereto;

Figure 2 is a side elevational view of the marking and lettering pen embodying this invention 60 and illustrates the manner in which the writing pen and feeding device are adjustably associated;

Figure 3 is a bottom plan view of the device embodying this invention showing the formation 65 of the writing point holder and illustrating further the configuration of the writing pen and the feeding device;

Figure 4 is a top elevational view of the feeding device showing the same detached from the writing pen;

Figure 5 is a top elevation view of the writing pen showing the feeding device detached;

Figure 6 is a longitudinal cross-sectional view taken on line 6—6 of Figure 1, looking in the direction of the arrows illustrating the invention 75 in detail;

Figure 7 is a transverse cross-sectional view taken on line 7—7 of Figure 2, showing the shape of the holder; and

Figure 8 is a transverse cross-sectional view 80 taken on line 8—8 of Figure 2, illustrating the manner in which the pen point is fastened to the holder.

In the drawing, wherein for the purpose of illustrating the invention and wherein like reference characters will be employed to designate like parts throughout the same, the reference character 5 will be generally employed to designate a writing pen handle shown in Figs. 1, 2 and 3 in dotted lines forming a handle for the pen. 90

On one end of the pen handle 5 is secured a metallic band 6 preferably hexagonal in cross-section to insure a frictional contact upon the end of the pen handle and also to permit a true longitudinal movement of the feeding and agitating device. The hexagonal band 6 is split as at 7 to insure a gripping action upon the end of the pen handle and to also allow for the forward end adjacent the split portion at 8 being return bent for securing the pen point 9 formed of celluloid or a regenerated cellulose material. The pen point 9 may be stamped from sheet material and the rear portion is bent arcuately as at 10 for being retained in the hexagonal holder 6. The forward portion may be more or less pointed as at 11 and may be provided with a transverse flat writing surface 12 having inwardly extending slits 13 for the purpose of assisting the feeding action.

110

It is to be understood, that the pen point 9 may be of any desired shape, but the best results have been obtained by the shape shown in the drawing.

5 Movably mounted upon the hexagonal pen point holder 6 is a band 14, preferably of the same configuration in cross-section as the band 6 so that the band 14 may be slid longitudinally thereof for the purpose of adjusting the feeding device.

10 Formed integral with the band 14 and extending laterally therefrom is a holder for the feeding device comprising a return-bent section 15 terminating in a flat portion 16 having inturned edges 17 for receiving the inner end of the feeding 15 device 18 as clearly shown in Fig. 4.

15 The feeding and agitating device extends forwardly from the reduced portion 18 in spaced relation from the writing pen 9 for a portion of its length and then is bent downwardly toward 20 the writing pen for another portion of its length as indicated at 19 so that the free end thereof nearly contacts with the free end of the writing pen 9. As shown in the drawing, the feeding and agitating device is preferably flat and enlarged as at 20 extending downwardly from the central line 21 to the converging line 22 thereby producing between the writing pen 9 and the feeding device a sizeable pocket for receiving the marking or lettering fluid which when in use is 25 fed to the point of the pen 9 and to the slits 13, extending inwardly from the writing surface 12. It will be observed that the pen point 9 is imperforate over its entire area and the writing end 12 thereof is provided with relatively short 30 slits. Also, the feeding device has an intermediate reduced portion enlarged at its outer end as at 20 to provide a reservoir overlying the writing end of the pen point. This arrangement of the pen point and feeding device assists the flow 35 of fluid and draws it toward the writing end of the pen point from the feeding reservoir, but does not allow the fluid to pass through to the underside in excess quantities, rendering it possible to control the flow of the fluid at the point 40 and further operates to prevent blots or pools of the fluid. The pen point remains unweakened by the provision of the relatively short slits in the writing end thereof and longer life is imparted 45

50

thereto as contrasted with the usual pen point of this character that is provided with holes, slots or other openings.

It has been found in practice that by moving the band 14 relative to the tubular holder 6 so that the free end of the feeding device 19 will be moved toward and away from the writing surface 12 that the amount of ink or marking fluid may be increased or decreased according to the type of lettering which is desired. 80

It has also been found in practice that due to the transparency of the fluid feeding device and the pen point the user thereof may have a clear vision of the surface upon which he desires to mark or letter thereby enabling him to produce lettering and marking with more accuracy which results in lettering or markings having more ornamental and pleasing characteristics. 85

90 I am aware that celluloid pen points have heretofore been employed, but it is believed that the pleasing effects obtained by the present invention are due to the feeding device in combination with the celluloid pen point due to the fact that the feeding device is formed of the same material thereby allowing both the same degree of flexibility and permitting the use of opaque colors. 95

100 It is to be understood that the form of the invention herewith shown and described is to be taken as a preferred embodiment of the invention and that various changes in shape, size, and arrangement of parts may be resorted to without departing from the spirit of the invention or the scope of the subjoined claim.

105 I claim:—

110 In a pen of the character described, a pen handle, a band secured to the handle, said band being longitudinally split and having return bent portions at the forward ends of the split, a pen point of flexible transparent material having its inner end within the band and engaged by the 115 return bent portions of the band to be retained therein, a second band slidable upon the first named band, said second band having a return-bent portion with inturned side edges, and an ink feeding device having one end slidably received in the return-bent portion of said second band, said feeding device overlying the pen. 120
